UNITED STATES PATENT OFFICE.

HENRY LANGE, OF QUINCY, ILLINOIS.

COMBINATION COAL AND GAS OVEN.

Application filed April 19, 1921. Serial No. 462,578.

To all whom it may concern:

Be it known that I, HENRY LANGE, a citizen of the United States, residing at Quincy, in the county of Adams and State of Illinois, have invented certain new and useful Improvements in Combination Coal and Gas Ovens; and I do hereby declare the following to be a full, clear, and exact description of the invention, such as will enable others skilled in the art to which it appertains to make and use the same.

This invention relates to cook stoves and ranges, and more especially to the ovens thereof adapted to be heated by coal or other solid fuel and also by gaseous fuel.

It is the object of the invention to provide an oven construction arranged to be heated from the exterior thereof, as usual, by the products of combustion when coal or other fuel is burned in the usual fire box, in connection with a hydrocarbon burner at the bottom of the oven for heating the oven from the interior by the flames and products of combustion rising from such burner, and novel means for obtaining an even distribution of the heat derived from the burner, so as to obtain uniform baking of the articles within the oven without the necessity for turning them, as is usually required in baking with a gas or hydrocarbon burner.

Another object of the invention is the provision of novel means combined with the oven for the circulation of the products of combustion from the burner so as to distribute the heat substantially uniformly throughout the oven above the burner, to provide for even baking.

A further object is the provision of novel means above the burner for spreading the flames and products of combustion, and for the passage of a portion of such products of combustion to enter the oven at another point, so as to obtain the even distribution of heat.

A still further object is the provision of a baffle within the oven above the burner for spreading the flames and products of combustion, and having a flue to register with a flue formed in one wall of the oven for carrying a portion of the products of combustion to an advantageous point for the distribution of the heat as aforesaid.

Another object is the provision of ventilating means for the oven, for the escape of the products of combustion after circulating within the oven, and novel means for

opening the ventilating means when gas is used.

The invention has for another object the provision of novel means for automatically opening the ventilating openings when the baffle is inserted into the oven for the heating of the oven by the gas burner, and for automatically closing said ventilating openings when said baffle is removed, thereby assuring of the opening of the ventilating means when gas is used for heating the oven, to avoid any possible danger of an explosion occurring, and also providing for the closing of said ventilating openings so that the products of combustion will not enter the oven when coal is used as fuel.

It is also an object of the invention to provide such an oven construction which will be comparatively simple and inexpensive in construction, which can be readily manufactured, and which will also be thoroughly practical, convenient, and efficient in use.

With the foregoing and other objects in view, which will be understood as the description proceeds, the invention resides in the construction and arrangement of parts, as hereinafter described and claimed, it being understood that changes can be made within the scope of what is claimed, without departing from the spirit of the invention.

The invention is illustrated in the accompanying drawings, wherein—

Fig. 1 is a front view of the oven portion of a stove or range, with the oven door removed, showing the improvements embodied in the oven.

Fig. 2 is a horizontal section on the line 2—2 of Fig. 4.

Fig. 3 is a vertical section on the line 3—3 of Fig. 2.

Fig. 4 is a vertical section on the line 4—4 of Fig. 1 on an enlarged scale.

Fig. 5 is a bottom plan view of the baffle, portions being broken away.

Fig. 6 is a vertical sectional detail taken on the line 6—6 of Fig. 7.

Fig. 7 is an elevation of one of the ventilating shutters or dampers in closed position.

The oven is built in the stove or range in much the same manner as heretofore, according to well known practice, to provide the baking chamber 11. The oven has a side wall or partition 12, the opposite side wall or partition 13, the back wall 14, the top or up-

per partition 15, and the bottom or lower partition 16. The front of the oven is closed by the usual door (not shown). The usual flue 17 for the products of combustion passing from the fire box, when coal or other similar fuel is burned in such fire box, extends over the top 15 of the oven, and a flue 18 extends downwardly from the flue 17 between the side wall 13 of the oven and the corresponding wall 19 of the stove casing. A flue 20 extends from the lower end of the flue 18 under the oven, between the oven bottom 16 and casing bottom 21. From the flue 20 the products of combustion pass through an opening 22 into the upwardly extending outlet flue 23 at the back of the stove casing in rear of the oven, and the back of the casing has another opening 24 leading to the flue 23 above the oven for direct outlet of the products of combustion. The opening 24 is closed, as usual, when baking, to compel the products of combustion to circulate around the oven for heating the oven from the exterior.

Disposed within and forming a part of the bottom 16 of the oven is a hydrocarbon burner 25 supplied with gas or other similar fuel by means of a supply pipe 26, and supplied with air from underneath the stove by means of an air flue 27 leading upwardly from the casing bottom 21.

The burner as shown is similar to the one disclosed in my copending application filed Jan. 19, 1921, Serial No. 438,414, although the present improvements are useful with any suitable burner at the bottom of the oven for heating the oven from the inside by products of combustion rising within the oven.

In carrying out the invention, a baffle 28 is disposed within the oven immediately above and near the bottom thereof, and is supported on the lower supporting lugs 29 carried by the side walls 12 and 13 for the adjustable support of the usual shelf (not shown) as well known. The side edges of the baffle can thus be slid over the lowermost lugs 29. The baffle 28 comprises a skeleton plate or casting having the openings 30 adjacent to its margin near the several edges of said baffle for the passage of the products of combustion from below the baffle upwardly along the side and back walls and front door of the oven. The baffle 28 has a central insulating panel 31 surrounded by the openings 30 and disposed over the burner for preventing the products of combustion from rising directly upward into the oven chamber, and spreading the flames horizontally under the panel to the openings 30. This panel 31 comprises the upper and lower metal sheets 32 and an intermediate sheet 33 of asbestos or other heat insulating material, whereby to avoid the excessive rising of the heat from the burner at the center of

the oven. The edge portions of the sheets 32 and 33 are secured or clamped on the baffle plate by means of bolts 34 or the like. The panel 31 will withstand the intense heat from the burner, and also reduces the penetration of the heat upwardly through the central portion of the baffle, as well as spreading the flames and products of combustion so as to pass upwardly through the openings 30.

The baffle 28 is provided with a flue 35 extending rearwardly from over the burner for carrying off part of the products of combustion from the burner. This flue 35 is relatively flat in cross section, as seen in Fig. 3, and has the upper and lower sections 36 and 37, the lower section being integral with the skeleton plate of the baffle, and the upper section 36 being clamped over the edges of the panel 31 where said panel is cut out to allow an opening or clearance for the flue. The section 36 and corresponding edges of the panel 31 are secured to the skeleton plate by means of bolts 38, or the like, and the lower flue section 37 has an opening 39 directly over the burner, so that a portion of the products of combustion rising from the burner will pass upwardly through the opening 39 in the bottom of the flue at the inner end of said flue, to pass rearwardly through the flue.

The back wall 14 of the oven has a vertical flue 40 extending upwardly from the rear end of the flue 35, and the flue 40 is also relatively flat. This flue 40 is formed by an outwardly or rearwardly offset portion 41 with which the back wall 14 is formed, and a plate 42 is disposed in front of and across said offset portion at the inner side thereof and has its side edges seated in rabbets 43 formed along the edges of said offset portion 41, so that said plate is flush with the back wall 14 at the interior of the oven. The plate 42 is secured to the back wall by means of one or more clamping bolts 44 engaging through said plate and offset portion. The back wall 14 is formed with an opening 45 leading forwardly between the lower end of the offset portion 41 and lower end of the plate 42, and the rear end of the flue 35 is extended and formed, as at 46, to slip or fit into the opening 45 when the baffle 28 is slid rearwardly into place within the oven, whereby to connect the flues 35 and 40.

The flue passage from the baffle is continued along the top 15 of the oven, by a flue 47 with which said top is provided to extend forwardly from the upper end of the flue 40. The flue 41 is formed similarly to the flue 40. Thus, the top 15 has an upwardly offset portion 48 and a plate 49 is disposed under and across said portion with its edges seated in rabbets 50 formed along the edges of the portion 130

48, so that the plate 49 is flush with the lower surface of the top 15. The plate 49 is secured in place by means of bolts 51 extending through said plate 49 and offset portion 48. The rear end of the flue 47 and upper end of the flue 40 are formed so that they register and fit together, at the upper rear corner of the oven, as seen in Fig. 4, and the forward end of the flue 47 terminates slightly short of the forward edge of the oven top 15. The plate 49 terminates short of the forward end of the offset portion 48, thereby leaving an opening 52 at the forward end of the flue 47 leading downwardly into the oven chamber 11 near the upper forward corner thereof.

The outwardly offset portions 41 and 48 of the back wall and top flues being integral with the back wall and top of the oven, will leave no openings or slits in said back wall and top, so that soot from the coal or other fuel will not enter the flues 40 and 47, as well as making the back wall and top solid, without open joints exposed to the products of combustion from the coal.

The ventilating means for the escape of the products of combustion from the oven include ventilating openings 53 in the side wall 13 of the oven at a suitable height above the bottom and also preferably spaced a suitable distance below the top of the oven. As shown, two of the openings 53 are provided near the back wall and door opening of the oven, respectively. The wall 13 has depressions 54 surrounding said opening in which shutters or dampers 55 are slidable and said shutters have downwardly extending shanks or stems 56 working in grooves 57 in the wall 13, and said stems have slots 58 receiving retaining rivets or members 59 carried by the wall 13, for holding said stems and shutters in place for vertical sliding movement. When the stems 56 are raised, the shutters 55 are opened to uncover the openings 53, and when the shutters and their stems drop or slide downwardly, the openings 53 are closed, as seen in Figs. 6 and 7.

In order to automatically control the shutters or dampers 55, the stems 56 are provided at their lower ends with outstanding cam lugs 60, and the baffle 28 is provided along the corresponding side edge with an upstanding flange 61, the rear end of which is inclined, as at 62, to form a cam. The arrangement is such that when the baffle 28 is slid into the oven, as indicated by broken lines in Fig. 7, the end 62 of the flange 61 will strike and move under the lugs 60, thereby raising the stems 56 and shutters 55, and said lugs will be supported by the flange 61, when the baffle 28 is in place within the oven, thereby holding the shutters 55 in open position. This automatically opens the ventilating means for the escape of the products of combustion and

gas, to avoid any possibility of an explosion occurring. When the baffle 28 is withdrawn, as when coal is used for fuel, the flange 61 being withdrawn from under the lugs 60, will permit the shutters 55 to drop and thereby close the openings 53. With the baffle removed, the oven is heated substantially the same as ordinarily when burning coal or other fuel in the fire box of the stove or range.

The advantage of the improvements resides in the use of the oven when heated by the gas burner 25. To use the burner, the baffle 28 is first inserted in the oven over the burner, to thereby raise the shutters 55 and to bring the rear end of the flue 35 into connection with the lower end of the flue 40. When the gas is lighted, the products of combustion rise against the panel 31 of the baffle, and a portion of the products of combustion will pass through the opening 39 into the flue 35, while the remainder of the products of combustion will be spread in all directions under the panel 31 to pass upwardly through the openings 30. The products of combustion spread by the baffle to the openings 30 will rise along the walls of the oven and the baffle will prevent the products of combustion and heat from rising excessively at the center of the oven, thereby making the heat more uniform throughout the area of the chamber 11. Furthermore, the products of combustion which enter the flue 35 will pass on up through the flue 40 and thence forwardly through the flue 47 to discharge back into the chamber 11 from the top near the front upper corner of the oven. The products of combustion passing through the flues are directed downwardly into the oven, whereby the articles or objects within the oven are heated from above as well as from below, for even baking. The products of combustion pass to one side through the openings 53 and on out by way of the flue 18. The circulation of the products of combustion thus obtained will distribute the heat substantially uniformly throughout the oven chamber, so as to provide for uniform baking, without being compelled to turn the articles around in the oven, as is the usual practice owing to uneven baking of such articles.

The surplus heat carried by the products of combustion from the burner through the circulating flues is delivered back into the oven chamber from above and at the front of the oven, to compensate for the natural tendency for the oven to cool behind the door. The oven naturally tends to be the coolest behind the door, because the door is exposed to the atmosphere, and by introducing the products of combustion from the flue 47, two objects are accomplished. First, the products of combustion are directed downwardly into the oven for

supplying heat to the articles from above, and second, the products of combustion are delivered behind the front door to equalize the heat within the front and rear portions of the oven chamber.

Having thus described the invention, what is claimed as new is:—

1. An oven, a burner at the bottom thereof, said oven having a flue for conducting products of combustion from one point to another point, and a flue member removably supported in the oven for conducting products of combustion from over the burner to said flue, said member extending over the burner and having a detachable connection with said flue, and said member being removable from the oven so as to leave no obstruction in the oven over the bottom thereof.
2. An oven, one wall of which is formed with a flue leading upwardly for discharging products of combustion into the oven at the top, a burner at the bottom of the oven, and a flue member supported slidably in the oven and adapted to be removed from the oven, said flue member being adapted to be positioned over the burner for conducting a portion of the products of combustion therefrom, said flue member and wall having a slip connection so that when the flue member is slid into place the products of combustion flow from the flue member into said flue.
3. An oven, a burner at the bottom thereof, a removable baffle to be disposed over the burner having a flue for conducting a portion of the products of combustion from the burner, and a flue in the oven with which the aforesaid flue is adapted to register when the baffle is disposed in the oven, the last named flue conducting the products of combustion from the first named flue to another portion of the oven.
4. An oven, a burner at the bottom thereof, said oven being formed with a flue for conducting products of combustion to enter

the oven at the top, and a removable baffle to be disposed within the oven over the burner for spreading the products of combustion, and having a flue for receiving a portion of the products of combustion from said burner and adapted to register with the aforesaid flue.

5. An oven, one wall of which has a flue leading upwardly for conducting products of combustion to enter the oven at the top, a burner at the bottom of the oven, and a baffle adapted to be slid into the oven over the burner, and having a flue to receive a portion of the products of combustion from said burner and to register with the lower end of the aforesaid flue.

6. An oven, one wall of which is provided with a flue leading upwardly for conducting products of combustion to enter the oven at the top, a burner at the bottom of the oven, and a baffle adapted to be slid into the oven above said burner and having a panel above the burner to spread the products of combustion, and also having a flue with one end arranged to receive a portion of the products of combustion from said burner and the other end arranged to register with the aforesaid flue.

7. An oven having a plurality of ventilating openings at one side, a gas burner for heating the interior of the oven, an individual shutter for each of said openings, and a baffle adapted to be slid into the oven over said burner between the sides of the oven, said shutters and one edge portion of the baffle having coöperating portions for opening the shutters in succession when the baffle is slid into the oven.

In testimony whereof I have signed my name to this specification in the presence of two subscribing witnesses.

HENRY LANGE.
